SETTING DEVICE

Hans Martin Sandkaulen, Sölfingen-Merscheid, Germany

Application November 13, 1950, Serial No. 195,163

Claims priority, application Germany November 17, 1949

3 Claims. (Cl. 90—24)

1

The present invention relates to an improved setting device and in particular to a setting in which a movable machine part may be set in one or another of a number of variable positions in sequence with accuracy.

Devices of this type are particularly suitable for use with machine tools, where a number of operations are effected on a work piece in sequence. Known devices of this type determining the degree of displacement of a tool support or the like have not given the precision desired, in that their individual parts engaging one with the other have been manufactured with too large a tolerance. Further, these parts have been subject to heavy wear, so that even the high tolerance of manufacture itself could not be maintained.

It is, therefore, one object of the present invention to provide a setting device made of parts which can be manufactured without tolerance.

It is another object of the present invention to provide a setting device which has a projection on the movable support which comes to rest against interchangeable stops as the support moves back into its operative position.

It is still another object of the present invention to provide a setting device which is relatively economical in its manufacture.

It is yet another object of the present invention to provide a setting device in which the support is carried on an axially displaceable rod mounted in a fixed frame, which rod has at one end a stop head, while the other is coupled with the displacing means.

It is a further object of the present invention to provide a setting device with an automatic change of the end stop by means of set screws carried on a turret head which is turnably mounted in the frame and which rotates reversely to the forward drive.

It is still a further object of the present invention to provide a setting device in which a feed pawl controlled by a cam engages at the end of the stroke with the free end of the supporting spindle lying opposite the projecting stop.

With these and other objects in view which will become apparent in the following detailed description, the present invention will be clearly understood in connection with the accompanying drawings, in which:

Figure 1 is a plan view of the setting device;

Fig. 2 is an end view thereof;

Fig. 3 is a fragmentary sectional view of the support with the tool;

2

Fig. 4 is a perspective view of a blade of a pinching shear, disclosing by example a workpiece, and:

Fig. 5 is a section along the lines 5—5 of Fig. 4.

Referring now to the drawings, the setting device comprises two side frames 1 and 2. A spindle 3 is axially displaceably mounted in the side frames 1 and 2. A support 4 is secured to the spindle 3 and slidably mounted on a supporting shaft 31. The spindle 3 carries at one of its ends a head 5 which is provided with a stop bolt 6, while its other end carries teeth 18. A pawl 7 engages the teeth 18, which pawl 7 is attached to a lever 20 which is pivoted on a pin 21 disposed on the frame. A spring 22 connected to one end of the lever 20 retains the latter in normal position. The pawl 7 is urged towards an abutment arm 24 by means of a spring 23, thereby disengaging the point of the pawl 7. The lever 20 is equipped with a roller 29 which engages a cam 25 secured to the main shaft 32 and turning in the cycle of the device.

A shaft 8 is also turnably mounted in the frames 1 and 2 and one end of the shaft 8 carries a disc 9. Bolt-like end stops 10 are disposed in a circular line on the disc 9, which stops 10 are of different length and exchangeable. The other end of the shaft 8 carries a control disc 11 on which coupling members 12 are disposed in a manner equivalent to the circular line and distances of the end stops 10. A finger 13 rotates with a shaft 14 in such manner that upon its rotation the finger 13 engages one of the coupling members 12. The main shaft 32 drives the shaft 14 by means of the gear drive 26, 27 and 28.

The spindle 3, which carries the support 4, is urged by a spring 16, one end of which is secured to an arm 17 of the support 4 while the other end is secured to the frame 2, in the direction to the right (Fig. 2), so that the stop bolt 6 engages one of the stops 10 of the disc 9.

The work holder 15 for the work piece 15 is subjected to an oscillating movement about a pivot 30 by means of the crank 33 which operates a connecting rod 31. The crank 33 is keyed to the shaft 32 and one end of the connecting rod 31 is eccentrically secured to the crank 33, while its other end is secured eccentrically to the workholder 15. The shaft 32 is driven by any convenient drive, as by example an electric motor 36 which rotates the crank 33 by means of a belt 38.

The tool 34, by example a cutting edge is clamped to the support 4 and may be manually 55 adjusted.

The present device is operated in the following manner:

The work piece 15', by example a blade of a pinking shear, is clamped to the work holder 15 by means of a clamping device (not shown), the work piece 15' thereby oscillating at a predetermined angle without performing a complete revolution.

The tool is mounted on the support 4. The spindle 3 is at first advanced by means of the pawl 7 which engages the teeth of the spindle 3 and in particular beyond the next following working position of the support 4. The stop bolt 6 is, thereby, lifted from the previously engaged stop 10. Now the finger 13 operates the control shaft 8 and also the turret head 9 to the extent until the next stop is in position opposite the stop bolt 6. Then the pawl 7 returns to its previous position. The spindle 3 is also withdrawn by means of the spring 16, until the stop bolt 6 engages the front face of the next stop 10.

The impact is taken up by the boss 19 which is secured to the frame 1.

The tool 34, preferably a cutting steel, is advanced towards the work piece 15' so that the tool cuts a particle from the work piece 15' during the oscillating rotary movement of the latter. Now the feeding device is put into operation. The cutting steel is moved by predetermined increments substantially parallel to the work piece 15' and particularly in the forward movement from the outer end to the center of the work piece blade and in the return movement from the center of the blade to its outer end, the tool 34 being fed axially toward the work piece 15', which is carried by the work holder 15, upon completion of each forward and return movement of the tool 34 in sideward direction. The forward and return movement of the tool 34 with its support is repeated as many times as required to achieve the desired distance and width of the grooves to be formed in the work piece 15'.

The tool 34 is disposed parallel to the axis of the work piece blade 15', so that the grooves cut by the tool 34 are concentrically disposed to the pivotal axis of the work piece blade 15'. In order to achieve this end, the work piece blade 15' is mounted on the work holder 15 in such manner that the axis of the pivot 30 coincides with the axis of the pinking shear pin (not shown). By this arrangement it is achieved that the grooves of the blade are disposed concentrically to the pivotal axis of the blade. The grooves formed in the same manner in a counter blade may thereby move through the grooves formed in the first blade during a shearing movement of both blades without any clamping of the latter.

As disclosed above, the movement of the spindle 3 carrying a support 4 is brought about by means of the pawl 7, the stroke of the latter conforming to the pitch of the teeth 18. The stop bolt 6 is thereby lifted further from the stops 10 than the length of the cutting stroke of the tool 34. Thereby, the head 5 performs a return movement by operation of the spring 16 to about the next stop 10 which in the meantime has been brought into position opposite the stop bolt 6. This effect is of essence in order to achieve continuously precise positions of the tool 34.

The tool 34 is fed axially toward the work piece 15' by hand, in conventional manner, and is also adjusted by hand. A rack 38 is disposed for this purpose in the support 4 and a meshing gear

37 is mounted in the upper portion 4' of the support 4, a dove-tail guide permitting movement of the upper portion 4' relative to the support 4 in axial direction of the tool 34, the latter being secured to the upper portion 4' of the support 4. The gear 37 may be operated by a hand wheel 35 disposed on one side of the support 4.

It is of course also possible to clamp the work-piece in the support 4 and the tool in the carrier 15 for the work piece. It is further obvious to provide the present device to existing machines, as lathes, shaping machines, or the like.

The present device lends itself particularly for such cases where adjacent grooves are formed on 15 a work piece which grooves must exactly be spaced from each other. The distances are exclusively determined by the stops 10 which are disposed on the turret head 9. The stops 10 may be easily formed to exact length and since no wear is experienced on the bolts a very accurate work is achieved even after a long time of their use.

While I have described one embodiment of the present invention, it is to be understood that this embodiment has been given by example only and not in a limiting sense, the scope of the present invention being determined by the objects and the claims.

I claim:

1. A setting device for the accurate setting of a tool support in relation to a work support to provide movement of one of said supports by predetermined increments for forming spaced grooves, comprising a frame, a spindle displaceably guided in the said frame, one of the said supports mounted on the said spindle, a stop head disposed on the free end of the said spindle, a rotatable plate mounted in the said frame opposite the said stop head, a plurality of end stops of differing length secured to the said rotatable plate, so that each of the said end stops may be axially aligned with the said stop head upon rotation of the said rotatable plate, a boss rigidly mounted on the said frame and disposed opposite to and in axial alignment with the said stop head and with one of the said end stops of the rotatable plate, the said boss being adapted to support the said rotatable plate with its end stop in operative position against end thrust, means for intermittent rotation of the said rotatable plate to put successively into operative position each of the said end stops, means for intermittently lifting the said stop head from the corresponding end stop of the said rotatable plate, and resilient means for returning the said stop head for engagement with the next of the said end stops upon rotating the said rotatable plate during the lifting interval of the said stop head.

2. The device, as set forth in claim 1, in which the said spindle has teeth in its rear and includes a cam-operated pawl engaging the said teeth and thereby bringing about the axial movement of the said spindle to perform the cutting strokes.

3. The device, as set forth in claim 1, in which the end stops of differing length are disposed on the said rotatable plate in circular arrangement.

HANS MARTIN SANDKAULEN.
